UNITED STATES PATENT OFFICE.

WILLIAM H. BENNETT, OF CALVIN, OKLAHOMA, ASSIGNOR OF ONE-EIGHTH TO JESSE A. CARTER, OF CALVIN, OKLAHOMA.

CONTROLLING MECHANISM FOR RAILWAY-TRAINS.

1,258,739.

Specification of Letters Patent. Patented Mar. 12, 1918.

Application filed October 18, 1916. Serial No. 126,364.

To all whom it may concern:

Be it known that I, WILLIAM H. BENNETT, a citizen of the United States, residing at Calvin, in the county of Hughes and State 5 of Oklahoma, have invented certain new and useful Improvements in Controlling Mechanisms for Railway-Trains, of which the following is a specification, reference being had to the accompanying drawings.

10 This invention relates to controlling mechanisms for railway trains; and it is an object of the invention to provide a novel and improved mechanism of this general character which is caused to operate automatically to bring a train to a standstill in the event the same should pass a predetermined point.

It is also an object of the invention to provide a novel and improved mechanism 20 of this general character having automatically operated means whereby the brakes of the train may be set and the operating power therefor cut off upon the train passing within a danger block or zone.

25 It is also an object of the invention to provide a novel and improved mechanism of this general character wherein the mechanism carried by the train will be caused to operate with a minimum of shock or jar and wherein the train will be required to 30 be brought to a full stop before the mechanism carried thereby may be reset.

Furthermore it is an object of the invention to provide a novel and improved mechanism 35 of this general character which may be readily applied to the train and to the track signal system with practically no change in existing standardized parts.

A still further object of the invention is 40 to provide a novel and improved mechanism of this general character whereby the same is caused to operate automatically through the medium of a trip member operatively engaged with a block system and 45 whereby said trip is thrown into an operative position when a danger signal is set.

A still further object of my invention is 50 to provide a mechanism of this general character having novel and improved means whereby the engineer's valve of an air brake system or the throttle controlling the operating power of the train, or both, will be so operated to cause the train to come to a standstill should said train pass beyond a 55 signal when set at danger.

The invention consists in the details of construction and in the combination and arrangement of the several parts of my improved controlling mechanism whereby certain important advantages are attained and 60 the device is rendered simpler, less expensive and otherwise more convenient and advantageous for use, all as will be herein-after more fully set forth.

The novel features of the invention will 65 hereinafter be definitely claimed.

In order that my invention may be the better understood, I will now proceed to describe the same with reference to the accompanying drawings, wherein—

70 Figure 1 is a view partly in elevation and partly in section illustrating a controlling mechanism for railway trains constructed in accordance with an embodiment of my invention;

75 Fig. 2 is a sectional view taken substantially on the line 2—2 of Fig. 1;

80 Fig. 3 is a fragmentary view partly in front elevation and partly in elevation of the mechanism as herein embodied;

85 Fig. 4 is a view partly in elevation and partly in section illustrating the trip member herein disclosed and an operating means therefor;

90 Fig. 5 is an enlarged view partly in section and partly in elevation of the trip member and its mounting;

95 Fig. 6 is a view in top plan of the trip member as disclosed in Fig. 5, the operating rod therefor being shown in fragment;

Fig. 7 is an enlarged view partly in elevation and partly in section illustrating the mounting of a rock arm herein included;

Fig. 8 is a detail view partly in section and partly in elevation disclosing the two-way valve herein employed with the adjacent operating means therefor;

Fig. 9 is a view partly in side elevation and partly in section illustrating a controlling mechanism constructed in accordance with a further embodiment of my invention;

Fig. 10 is a sectional view taken substantially on the line 10—10 of Fig. 9;

Fig. 11 is a fragmentary view partly in elevation and partly in section illustrating certain details of construction as included in the second form of my invention; and

Fig. 12 is a fragmentary view in perspective illustrating certain details of con-

struction comprised in the connection between the signal and the trip as herein included.

As disclosed in the accompanying drawings, L is a fragmentary and diagrammatic representation of a locomotive, the frame F of which supporting the vertically disposed rock shaft 1 provided at its lower end with an arm 2 adapted to contact with 10 a trip T positioned adjacent the trackway in the event that the signal adjacent said trip T may be set at danger.

As herein embodied, the trip T denotes an elongated member pivotally supported 15 intermediate its length by the base or bracket 3 secured to a cross tie C comprised in the trackway, the pivotal mounting for the trip T consisting of a rod 4 rotatably supported by said base or bracket 3 and provided with 20 a crank or rock arm 5 connected, through the medium of the rod 6 or its equivalent, with the operating rod 7 of the semaphore 8 or other signal included in a block system. It will be perceived that when the rod 7 is 25 moved to throw the semaphore 8 into danger position, the trip T will be rocked into an elevated or substantially perpendicular position so that the same will intersect the line of travel of the arm 2 of the shaft 1.

30 The upper end of the shaft 1 is provided with a crank arm 9 which is operatively connected through the medium of the link 10 with the crank arm 11 carried by the stem 12 of the valve 14 interposed in the 35 pipe line 15 leading from a suitable source of air under pressure and preferably one of the reservoirs or tanks employed in the air brake system of the train and to one preferably carried by the locomotive valve.

40 The valve 14 is of a two-way type so that when the same is thrown in one position under the influence of the contact between the trip T and the arm 2 of the shaft 1, a continuous flow of air will be permitted 45 through the pipe line 15 and when said valve is reset to close the pipe line 15 communication will be had with the atmosphere so that the air within the cylinder A may escape, it being understood that the pipe 50 line 15 is in communication with said cylinder A at an end or head thereof.

55 Mounted within the cylinder A is a piston P of any ordinary or preferred type and which is connected to the rod 16 extending through the end or head of the cylinder A remote from the line 15 and the outer end of said rod 16 is pivotally engaged to the arm or link 17 which, as disclosed in the embodiment of my invention illustrated in 60 Figs. 1 to 8, is also pivotally engaged with the arm 18 loosely mounted on the horizontally disposed shaft 19 rotatably supported by and below the floor 20 of the cab of the locomotive.

65 Fixed to the shaft 19 is a rock arm 21 and

interposed between the arm 18 and the rock arm 21 and encircling the shaft 19 is a coil spring 22 having its extremities secured to said arm 18 and rock arm 21, said spring 22 being of such strength as to transmit the 70 rotary movement of the arm 18 to the rock arm 21 so that the shaft 19 will be caused to move. By the use of the spring 22 it will be perceived that the abrupt contact between the arm 2 of the shaft 1 and the trip T will be 75 substantially absorbed by the spring 22 so that the remaining mechanism carried by the locomotive will not be injured by the jar or shock incident to the coaction between the arm 2 and the trip T. 80

It might be well to state at this time that the trip T is provided with the rotatable sleeve 23 with which the arm 2 directly contacts so that said arm 2 may coact with the trip T with a minimum of friction. 85

The shaft 19 is also provided with a second rock arm or crank 24 provided with a trunnion or wrist pin 25 working within a slot 26 produced in the lower end of the vertically disposed lever 27 pivotally mounted 90 intermediate its length, as at 28, for rocking movement. The upper end portion of the lever 27 is adapted to engage with the operating arm or lever 29 of the engineer's valve V, said lever 27 and valve V being of 95 a type as employed in the well known New York air brake system.

30 denotes a guide member coacting with the lever 27 and which is preferably positioned above the pivotal mounting 28 of said 100 lever.

It will be perceived that as the lever 27 is caused to rock under the influence of the rod 16, the operating arm or lever 29 will be moved in such a direction as to cause the 105 brakes comprised in the air brake system to be set.

The piston P and its coacting rod 16 are normally maintained in a retracted position and are automatically returned to such position upon resetting of the valve 14 through the medium of the retractile members 31 herein disclosed as conventional coil springs positioned at opposite sides of the cylinder A and interposed between and operatively 110 connected to the cross bar 32 carried by the rod 16 and the opposite end portion of the cylinder A.

The outer end portion of the rock arm 21 has pivotally connected thereto the rod 33 120 of the piston P' mounted within the cylinder 34 pivotally supported by and below the floor 20 of the cab of the locomotive. The cylinder 34 and the piston P' coact as an air check to provide further means to absorb 125 the sudden shock and jar incident to the operation of the mechanism when the arm 2 is brought into contact with the trip T.

B denotes a conventional type of operating lever for the throttle valve of a locomotive- 130

5 tive and which is provided with the handle H for releasing the lever from a locked position, and connected to said handle H is a flexible member 35 which passes around 10 a suitable positioned guide pulleys 36 and secured to the arm 18, whereby it will be perceived that as said arm 18 is swung or rocked under the influence of the operation of the arm 2 by contact with the trip T, the 15 lever B will be released and the throttle valve adjusted into a closed position for a purpose which is believed to be clearly apparent to those skilled in the art to which my invention appertains.

15 Connected to the flexible member 35 is a retractile member 37 herein disclosed as a conventional coil spring and which is also anchored to a suitable part of the locomotive L and which serves to normally maintain 20 the portion of the flexible member 35 immediately adjacent the lever B sufficiently slack so that under normal conditions the engineer may adjust said lever B without swinging or rocking the arm 18. It will also 25 be understood that the movement of the arm 18 is sufficient, when moved as before stated, to take up the slack of the flexible member 35 and also to impart the requisite movement to the lever B to close the throttle 30 valve.

As disclosed in Figs. 9 to 11, my improved mechanism is employed in connection with the well known Westinghouse air brake system and as disclosed in this form of my invention, the arm or link 17 is pivotally engaged with an arm 38 loosely mounted upon the vertically disposed shaft 39 suitably supported by the locomotive structure.

Fixed to the shaft 39 at a predetermined 40 point below the arm 38 is a rock arm 40, and interposed between said arms 38 and 40 and encircling the shaft 39 is a coil spring 41 which is secured to said arms 38 and 40 and of sufficient strength to transmit the rotary 45 force imparted to the arm 38 to the arm 40 so that the shaft 39 will be caused to rock or rotate.

The upper end portion of the shaft 39 is provided with an angular extension 42 50 adapted to engage with the handle 43 of the engineer's valve E. By this arrangement it will be perceived that as the shaft 39 is caused to rotate or rock under the influence of the cylinder A and the coacting piston P, 55 the shaft 39 or more particularly the angular extension 42 thereof, will so move the handle 43 as to cause the brakes comprised in the system to be set.

The arm 40 is pivotally engaged with the 60 rod 44 of the piston P² within the cylinder 45 pivotally supported by and positioned below the floor 20 of the cab, said cylinder 45 and piston P² coacting to afford an air check to further absorb the shocks or jars 65 incident to the operation of the mechanism.

The arm 38 has also connected thereto a suitably guided flexible member 46 coacting with the handle H' of the operating lever of a throttle valve as has hereinbefore been set forth in the first embodiment of my invention.

Each of the arms 18 and 38 is held against movement longitudinally of its shaft through the medium of a set screw 47 or the like disposed through the connected end of 75 said arm and extending within an annular groove 48 produced in the shaft.

I also find it of advantage to provide the cylinders 34 and 35 with the valve controlled vent 49 to control the escape of air therefrom. By this arrangement the escape of air from the cylinder may be timed and this is of particular advantage as some roads run at a less speed than others and therefore the air could not escape as fast so that more 85 time will be allowed for the train to ease down to a standstill.

While the rod 6 may be engaged with the operating rod 7 in any desired manner, I 90 find it of particular advantage to employ the arrangement as illustrated in Figs. 4 and 12, and wherein the upper end of the rod 6 is forked, as at 50, and pivotally engaged with the cross pin 51 intersecting the pin 52 which coacts with the forked end 53 of the lever 95 54, as is believed to be clearly illustrated in Fig. 12.

The lever 54 is mounted for rocking movement intermediate its length through the medium of the bracket 55 and has its inner 100 end forked, as indicated at 56, to straddle the operating rod 7, and said fork 56 is interposed between the pins 57 carried by the rod 7 and in predetermined longitudinal spaced relation thereon. It will be perceived 105 that when the semaphore is in danger position as illustrated in Fig. 4, the lower pin 57 will coact with the lever 54 to adjust the trip T into an upright or operative position, but should the signal or semaphore be adjusted to a caution position, no movement 110 will be imparted to the lever 54, as the space between the pins 57 permits the necessary movement of the rod. However when the signal or semaphore 8 is brought to a clear 115 position the upper pin 57 will contact with the lever 54 and cause the same to adjust the trip T to a lowered or inoperative position.

From the foregoing description, it is thought to be obvious that a controlling 120 mechanism constructed in accordance with my invention is of an extremely simple and comparatively inexpensive nature and is particularly well adapted for use by reason of the convenience and facility with which 125 it may be assembled, and it will also be obvious that my invention is susceptible of some change and modification without material departure from the principles and spirit thereof and for this reason I do not 130

wish to be understood as limiting myself to the precise arrangement and formation of the several parts herein shown in carrying out my invention in practice, except as hereininafter claimed.

I claim:

1. A mechanism of the character described comprising, in combination, a valve provided with a controlling lever, a rock shaft, an arm loosely mounted on the shaft, a rock arm fixed to said shaft and operatively engaged with the lever, and a spring encircling said shaft and interposed between said arms, said spring being secured to the arms whereby the movement of the first named arm will impart movement to the second named arm and the shaft.
2. A mechanism of the character described comprising, in combination, a valve provided with a controlling lever, a rock shaft, an arm loosely mounted on the shaft, a rock arm fixed to the shaft and operatively engaged with the lever, and a yielding connection between said arms whereby the first named arm has a movement independently of the second named arm.
3. A mechanism of the character described comprising in combination, a valve provided with a controlling lever, a rock shaft, an arm loosely mounted on the shaft, a rock arm fixed to the shaft and operatively engaged with the lever, a yielding connection between said arms whereby the first named arm has a movement independently of the second named arm, and automatic means co-acting with the loosely mounted rock arm for imparting movement thereto.
4. A mechanism of the character described comprising, in combination, a valve provided with a controlling lever, a rock shaft, an arm loosely mounted on the shaft, a rock arm fixed to the shaft and operatively en-

gaged with the lever, a yielding connection between said arms whereby the first named arm has a movement independently of the second named arm, and pneumatic means co-acting with the loosely mounted rock arm for imparting movement thereto in one direction.

5. A mechanism of the character described comprising, in combination, a valve provided with a controlling lever, a rock shaft, an arm loosely mounted on the shaft, a rock arm fixed to the shaft and operatively engaged with the lever, a yielding connection between said arms whereby the first named arm has a movement independently of the second named arm, pneumatic means co-acting with the loosely mounted rock arm for imparting movement thereto in one direction, and means co-acting with the loosely mounted rock arm for moving the same in an opposite direction.

6. A mechanism of the character described comprising in combination, a valve provided with a controlling lever, a rock shaft, an arm loosely mounted on the shaft, a rock arm fixed to the shaft and operatively engaged with the lever, and a yielding connection between said arms whereby the first named arm has a movement independently of the second named arm, automatic means co-acting with the loosely mounted rock arm for imparting movement thereto, and means co-acting with the loosely mounted rock arm for limiting the movement thereof under the influence of the automatic means.

In testimony whereof I hereunto affix my signature in the presence of two witnesses.

WILLIAM H. BENNETT.
